UNITED STATES PATENT OFFICE

96,018

DESIGN FOR A TELEPHONE RECEIVER BASE

Philip J. Cannon, Cincinnati, Ohio

Application March 16, 1935, Serial No. 55,900

Term of patent 7 years

To all whom it may concern:

Be it known that I, Philip J. Cannon, a citizen of the United States, residing at Cincinnati, in the county of Hamilton and State of Ohio, have invented a new, original, and ornamental Design for a Telephone Receiver Base, of which the following is a specification, reference being had to the accompanying drawing, forming a part thereof.

Figure 1 is a perspective view of the design for telephone receiver base.

Figure 2 is a side elevation of the design.

Figure 3 is a front elevation of the design.

I claim:

The ornamental design for a telephone receiver base as shown.

PHILIP J. CANNON.
